CAN PUNCH OR THE LIKE

George Coplen, Cripple Creek, Colo.

Application May 27, 1957, Serial No. 46,369

Term of patent 7 years

(Cl. D44—29)

Fig. 1 is a side elevational view of a can punch showing my new design;

Fig. 2 is a top plan view thereof;

Fig. 3 is a bottom plan view;

Fig. 4 is a sectional view taken on line 4—4 of Fig. 2;

Fig. 5 is a sectional view taken on line 5—5 of Fig. 1; and

Fig. 6 is a sectional view taken on line 6—6 of Fig. 1.

I claim:

The ornamental design for a can punch or the like, as shown.
